UNITED STATES PATENT OFFICE.

HORACE W. NICHOLS AND SAMUEL BRIGGS, OF FOLCROFT, PENNSYLVANIA.

AUTOMATIC TROLLEY-CONTROLLING DEVICE.

SPECIFICATION forming part of Letters Patent No. 769,009, dated August 30, 1904.

Application filed January 4, 1904. Serial No. 187,658. (No model.)

To all whom it may concern:

Be it known that we, HORACE W. NICHOLS and SAMUEL BRIGGS, citizens of the United States, residing at Folcroft, county of Delaware, and State of Pennsylvania, have invented a certain new and useful Improvement in Automatic Trolley-Controlling Devices, of which the following is a specification.

Our invention relates to a new and useful improvement in automatic trolley-controlling devices, and has for its object to provide a device to be attached to the car which will automatically pull the trolley down below the wire at any time the trolley leaves the wire and will also keep the rope taut, so as to take up the slack as the trolley rises or falls with the rise and fall of the wire.

With these ends in view this invention consists in the details of construction and combination of elements hereinafter set forth and then specifically designated by the claims.

In order that those skilled in the art to which this invention appertains may understand how to make and use the same, the construction and operation will now be described in detail, referring to the accompanying drawings forming a part of this specification, in which—

Figure 1 is a perspective view of our device attached to the car; Fig. 2, a horizontal section through our improved device; Fig. 3, a vertical section taken on the line 3 3 of Fig. 2; Fig. 4, a vertical section taken on the line 4 4 of Fig. 2.

Our device is intended as an improvement on application for patent filed by Horace W. Nichols September 9, 1903, Serial No. 172,431. In the application referred to provision was only made for automatically pulling the trolley down below the wire at any time the trolley leaves the wire; but in this application provision is also made for keeping the trolley-rope taut as the trolley rises and descends with the irregularities of the wire.

It is a well-known fact that it is advantageous to keep the trolley-rope taut, for where slack is allowed in the rope for the rise and fall of the trolley the rope is liable to catch upon some protruding portion of the car, especially when the wind is blowing, and then

when the trolley-wire inclines upward the trolley cannot follow the same, as the rope being caught over the projection will prevent the rise of said trolley and therefore disconnect the current. With our improved invention the trolley-rope is kept taut at all times, and therefore the trolley is free to follow the wire in all its irregularities.

A represents the casing, which may be made of any suitable shape or design to properly contain the operating parts, this casing being provided with a slot A', formed through the upper side, through which the trolley-rope extends to the trolley. This casing may be permanently secured to the dashboard of the car, but would probably be made removable, so as to be changed from one end of the car to the other when the trolley is reversed.

B is an axle journaled at each end in the casing. This axle is normally held stationary on account of a ratchet-wheel B', secured to the axle, a pawl C engaging the teeth of the ratchet-wheel B', said pawl C being journaled to the casing, and as the tendency of the axle is always to revolve in one direction against the pawl said pawl will hold the axle stationary.

D is a hollow cylinder having an elongated hub D', which is journaled upon the axle B. Within said hollow cylinder D is arranged a coil-spring E, one end of said coil-spring being attached to the cylinder and the other end of the spring being attached to a collar F, which collar has a square opening formed therethrough adapted to slip over the end of the shaft and fit upon a squared portion of the shaft, so that virtually one end of the spring E is attached to the cylinder and the other end to the normally stationary shaft.

G is a ratchet-wheel formed with the cylinder D.

H is a pawl adapted to engage the teeth of the ratchet-wheel when said pawl is pressed downward into engagement with the ratchet-wheel and hold the cylinder against the action of the spring E. The teeth of the ratchet-wheel G are slightly undercut, so that the pawl will be held in engagement with the ratchet-wheel by the tension of the spring E.

H' is a spring adapted to so act upon the

pawl H as to tend to throw the pawl out of engagement with the ratchet-wheel G. Therefore at any time the tension of the spring E is relieved, so that the ratchet-wheel G is given a slight retrograde movement, the pawl H will spring out of contact with said ratchet-wheel and allow the spring to act.

I is a drum journaled at one end around the cylinder D and at the other end upon a shaft B.

10 J is a coil-spring connected at one end to the drum I and at the other end to the hub D' of the cylinder D. A collar similar to the collar F may fit over the hub D' and the spring J be attached to said collar, if so desired. Said spring J is coiled in the same manner as the spring E, so as to tend to give the drum I the same revolution as the spring E tends to give to the cylinder; but said spring J is a much lighter spring than the 20 spring E, and the spring J is not controlled by any ratchet-wheel.

K is the trolley-rope, which is secured at one end to the drum I and at the other end to the trolley.

25 In operation the trolley-rope is first wound around the drum I, and then by pulling upon the rope K, so as to unwind the same from the drum I, the drum I will be revolved until the spring J is wound up tight, and then the 30 cylinder D will be revolved, through the spring J, so as to wind up the spring E, and after the spring E has been wound to a predetermined point by throwing the pawl H in engagement with the ratchet-wheel G said spring E is held

35 under tension; but the spring J is free to revolve the drum I and wind the rope upon the drum, and as the spring J is weaker in tension than the spring which holds the trolley against the trolley-wire any rise in the trolley will 40 cause the drum I to be revolved, so as to unwind the rope therefrom, and as the trolley descends with a fall in the wire the drum I will revolve under the tension of the spring J, so as to take up the slack in the rope K; but should the trolley at any time leave the wire the upward pull 45 upon the rope K would revolve the drum I until the spring J is wound tightly, and the momentum of the upward movement of the trolley-pole would cause a slight retrograde 50 movement of the cylinder D after the spring J had been tightly wound, and this slight retrograde movement would be sufficient to allow the spring H' to act to throw the pawl H out of engagement with the ratchet-wheel G, 55 leaving the spring E free to act, and as this spring E is of greater tension than the spring which controls the trolley-pole the spring E in unwinding would, through the spring J, revolve the drum I in the opposite direction,

60 so as to wind the rope K upon the drum and pull the trolley downward below the trolley-wire, and then in order for the conductor to replace the trolley upon the wire it is only necessary for the conductor to pull the rope 65 out of the controller until both springs have

been wound, and then by placing the pawl H into engagement with the ratchet-wheel E and placing the trolley upon the wire when the rope is released the spring J will wind the slack in the rope upon the drum I, and the car is free to proceed upon its journey.

In the drawings we have shown a device whereby the pawl H may be automatically thrown into engagement with the ratchet-wheel instead of requiring separate operations to place the same in engagement. This we accomplish by connecting the pawl H with a rod L, which extends across the controller longitudinally, and the trolley-rope K passes behind this rod L, as shown in Figs. 3 and 4, 80 and when the rope is pulled inward toward the car by the conductor said rope impinging upon the rod L will force the pawl H in engagement with the ratchet-wheel and hold it in engagement while the springs are being 85 wound, and then when the rope is released the ratchet-wheel E will catch the pawl and hold it in engagement with itself. The purpose of the ratchet-wheel B', secured to the shaft and the pawl C, is for preventing any 90 damage to the spring should the trolley-rope break at any time, for if the trolley-rope should break the springs would rapidly unwind, and if the shaft B were absolutely stationary when the springs were fully 95 unwound the momentum of the drum I might break the springs, but when it is constructed with the ratchet-wheel B' after the drum I has obtained some momentum the shaft B will revolve with the drum, and therefore 100 provide against any sudden stop of the spring.

In long cars the trolley does not extend beyond the end of the cars, and therefore the trolley-rope must come in contact with the edge of the roof of the car in passing to the 105 trolley. In Fig. 5 we have shown a device for guiding the trolley-rope in such instances, which consists of a bracket M, secured to the edge of the roof of the car, and in this bracket is journaled a roller N, over which the rope 110 passes. The ends M' of the bracket extend outward beyond the roller, so as to limit the lateral motion of the rope. Thus no matter if the trolley is a considerable distance one side of the car the rope will be held by the ends 115 M' over the controller.

Of course we do not wish to be limited to the exact construction here shown, as slight modifications could be made without departing from the spirit of our invention.

Having thus fully described our invention, what we claim as new and useful is—

1. In combination with a trolley-car, a drum journaled upon the car, the lower end of the trolley-rope being coiled upon said drum, a spring less in strength than the trolley-pole spring adapted to act upon the drum so as to rotate the same at all times to take up the slack in the trolley-rope, a spring stronger than the trolley-pole spring adapted to act 130

upon the drum so as to wind the trolley-rope thereon, a cylinder containing said spring and to which one end of said spring is connected, a ratchet-wheel connected to said cylinder, a pawl normally holding said ratchet-wheel against rotation, and means for disengaging said pawl from the ratchet-wheel when the trolley leaves the wire, as and for the purpose specified.

10 2. In a device of the character described, a removable casing adapted to be secured to the trolley-car, said casing being provided with a slot in its upper end through which the trolley-rope extends, a drum journaled upon the interior of the casing, a stationary axle upon which the drum is journaled, a cylinder journaled upon the axle, a coil-spring arranged within the cylinder, said spring being stronger than the trolley-pole spring upon the top of the car, one end of said spring being attached to the cylinder and the other end to the stationary axle, a ratchet-wheel carried by the cylinder, a pawl adapted to engage the ratchet-wheel and normally hold the spring under tension, a coil-spring less in strength than the trolley-pole spring, one end of said spring being attached to the drum and the other end to the cylinder, the lower end of the trolley-rope adapted to be wound around the drum, and both springs adapted to rotate the drum in the proper direction for winding the rope upon the same, the lighter spring always being free and adapted to take up the slack in the rope, and means for disengaging the pawl from the ratchet-wheel when the trolley leaves the wire and the trolley-pole springs upward, as and for the purpose specified.

3. In combination with a trolley-car in a device of the character described, a removable casing adapted to be secured to the trolley-car, said casing being provided with a slot in its upper end through which the trolley-rope

extends, a drum journaled upon the interior of the casing, an axle upon which the drum is journaled, a cylinder arranged upon the interior of the drum and also journaled upon the axle, a coil-spring arranged within the cylinder, one end of which is attached to the cylinder and the other to the axle, a ratchet-wheel secured to the cylinder, the teeth of said ratchet-wheel being slightly undercut, a pawl pivoted to the casing adapted to normally engage the ratchet-wheel and be held in engagement by the tension of the spring, a small spring for throwing the pawl out of engagement with the ratchet-wheel when the tension is released momentarily, a second coil-spring of less strength than the spring operating the trolley-pole, one end of said spring being attached to the drum and the other end to the cylinder, both of said springs adapted to act to revolve the drum in one direction, the second spring being always free to act, the trolley-rope adapted to be wound upon the drum, the second or lighter spring acting so as to take up the slack in the trolley-rope, a longitudinal rod connected to the pawl behind which the trolley-rope passes so that when the trolley-rope is pulled inward toward the car, the rope will act upon the rod to force the pawl into engagement with the ratchet-wheel, a ratchet-wheel secured to the axle, a pawl pivoted to the casing engaging the ratchet-wheel so as to hold the axle stationary against the action of the springs, as and for the purpose specified.

In testimony whereof we have hereunto affixed our signatures in the presence of two subscribing witnesses.
